METHOD AND MEANS FOR FORMING SELVAGE

John R. McDowell, Knoxville, Tenn., assignor to
George W. Dunham, Wilton, Conn.

Application June 15, 1956, Serial No. 591,637

6 Claims. (Cl. 139—127)

This invention relates to looms and more particularly to a method and means for forming selvage in a fabric as the fabric is being woven in a loom in which the filling is supplied from sources outside of a shuttle or filling-inserting means. In certain types of such looms a filling-inserting means or pilot picks up a leading end of a filling thread at one side of the loom and carries it across the loom where the leading end is freed from the pilot and a filling thread from a separate source of supply is picked up and carried across the loom in a reverse direction.

An object of the invention is to form a selvage by interweaving ends of fillings in the fabric as the weaving of the fabric progresses.

Other objects and advantages will be apparent as the nature of the invention is more fully disclosed.

In accordance with the invention, an end of an inserted filling thread or weft is turned into an open shed of warps after the inserted filling thread has been beaten into the fell of the fabric and the warps have been reversed. The end is freed from a pilot during the movement of the lay away from the fell of the fabric as the pilot to which it is attached is carried backwardly with the lay. The free end is inserted in the shed before the pilot is projected towards the opposite side of the loom to insert another filling thread. During the following forward movement of the lay, and as the open shed of warps is closing, or at the point of closing, the end of the thread which was turned in between the open warps is advanced toward the fell of the fabric by a wire located on the lay inwardly from the edge of the fabric a distance corresponding to the desired width of the selvage. A hook on the end of the wire pulls the terminal portion of the inserted end downwardly through the lower side of the shed as the lay and the wire continue to move forwardly and downwardly. The portion of the turned-in end remaining between the warps is beaten up at the same time that the later-inserted filling thread is beaten up as the lay completes its forward stroke. The selvage at the other edge of the fabric is formed in the same manner in alternate cycles of the loom. The ends of the fillings which have been drawn through to the underside of the fabric are subsequently cut or otherwise removed from the cloth.

The principle of the invention will be better understood from the following description, taken in connection with the accompanying drawing in which an embodiment of the invention has been set forth for purposes of illustration.

In the drawing, Fig. 1 is an elevational section through a lay as seen from the left hand side of the left hand lay sword;

Fig. 2 is a top view of part of the lay and of the left edge of a fabric, schematically illustrated, as seen from above the lay;

Figs. 3, 4, 5 and 6 diagrammatically illustrate four stages of weaving during the backward and forward movements of the lay;

2

Fig. 7 is an enlarged sectional view of a valve and valve-operating mechanism.

Fig. 8 is an enlarged detail.

The loom with which the present invention is employed is a high speed loom in which a pilot-projecting mechanism is mounted at each end of a lay for projecting a pilot or weft carrier to and fro along the lay. The pilot is projected from opposite ends of the lay in alternate cycles of the lay and in each cycle a filling thread is carried by the pilot from one or the other of two sources of supply convenient to the respective ends of the lay. In succeeding cycles the pilot picks up a filling thread from a source of supply adjacent one end of the lay and carries it to the projector at the other end of the lay where the pilot is held until after the leading end of the thread has been released therefrom. In disclosing the present invention it will suffice to describe the loom parts generally and with respect to a projector located at one end of the lay.

The lay 10 is supported by a pair of lay swords, one of which is illustrated at 11 in Fig. 1. The lay swords are mounted on a pivot shaft 12 journaled in a pair of loom sides of which the right-hand loom side 13 is illustrated in Fig. 1. Each lay sword is actuated from a connecting rod 14 pivotally connected at its front end to the sword by a pin 15 and pivotally connected at its rear end to a crank 16 carried by a power-driven crankshaft 17 which makes one revolution for each cycle of the loom. The upper ends of the swords are connected by a rail 18 against which the upper edge of a reed or comb 19 is clamped by a bar 20. The lower edge of the reed 19 rests upon a plurality of brackets 21 which are secured to the lay by bolts 22. The lower edge of the reed and a spacing bar 23 are firmly clamped in position on the brackets.

The pilot 24 (Fig. 2) is guided in a straight course lengthwise of the lay by the wires of the reed and by a plurality of spacially arranged guides 25 which are carried by the lay. The notches 26 in the guides 25 face the reed and provide together with the reed a tunnel-like raceway for guiding the course of the pilot from one projecting mechanism to the other. Each guide is formed from a flat plate-like stock of a durable material, such as sheet steel, and their edges are rounded to avoid interference with the warps as they move between the warps as the lay is reciprocated. As shown in Fig. 2 the pilot 24 is contained in the projector box 27 of the left hand projecting mechanism.

As is well understood, the warp harnesses 28 manipulate the various warps 29a and 29b upwardly and downwardly in timed relationship to the movement of the lay. The shed cycling of the present loom is approximately such that when the crank 16 is at 0° (360°) and the lay 10 is in full front position, the shed is fully open. The shed remains fully open until the lay is in full back position with the crank at 180°, at which position the shed starts to close and becomes fully closed when the crank has rotated to the crank position of 270°. The shed then reverses and starts to open and becomes fully open when the crank completes a revolution at the crank position of 360° and the lay is in full front position.

As illustrated in Figs. 1, 2 and 3, the position of the lay corresponds to the position of the crank after movement through an arc of about 75° from full front position. As the lay moved from the fell of the fabric 30 the leading end 31 of the filling thread 32 was pulled from the gripping means 33 (a hook and a spring member) on the pilot and extended substantially centrally of the open shed (Fig. 3). As the end is freed from the pilot it is blown into the open shed by a blast of air and disposed substantially as shown at 31a, Fig. 2.

The air jet is so timed that it will be effective on the

thread end as the end comes free from the pilot. The air is supplied by a compressor (not shown) which delivers compressed air to a supply pipe 35 having connection with a branch pipe 36 supplying air under pressure to a valve adjacent the right end of the lay and a branch 37 supplying air under pressure to a valve 38 adjacent the left end of the lay. The valves are normally closed and, as shown in Fig. 7, each valve is opened by an actuator 39, mounted on the lay, as the lay moves past the valve. In the position of the lay shown in Figs. 2 and 3, the valve 38 is open and air is flowing through the conduit 40 and from the nozzle 41 whereby to deflect the end 31 of the filling thread into the open shed.

The lay carries a needle-like wire 42 mounted just forward of the guides 25 adjacent each edge of the fabric. Each wire is mounted on an adjustable bracket 43 which is attached in a fixed position on the lay at a distance inwardly from the edge of the fabric corresponding to the desired width of a selvage 44. The wire 42 is disposed in a plane perpendicular to the pivotal axis of the lay and moves into and out of the shed as the lay reciprocates.

The upper end of the wire 42 is tapered to facilitate its entry between adjacent warps and a notch is provided to form a hook 45 for engaging the filling thread end 31a. In Fig. 5 the lay is moving forwardly and the shed has closed over the blown-in thread end 31a. As the lay 10 continues forwardly and downwardly the wire 42 advances the previously blown-in end 31a towards the fell of the fabric and hooks onto the thread end. As the hook 45 passes below the plane of the fabric the hook rakes the terminal portion 46 of the thread downwardly below the closed warps. The closed shed exerts sufficient restraint on the hook-engaged thread to cause that portion of the end which remains interwoven in the fabric to form a tight selvage. Subsequently, the various loose ends 46 are cut or otherwise removed from the fabric.

The position of the wire 42 laterally of the lay affects the tightness of the selvage because the restraint of a closed shed on a blown-in thread end varies as the reed approaches the fell of the fabric. The wire 42 is adjustably mounted on the lay so as to be positionable closer to or further away from the fell for any given position of the lay with respect to the fell. As best seen in Fig. 8, the bracket 43 is mounted for adjustment on the lay. A shim 47 is located between the depending leg 48 of the bracket 43 and the front side of the lay, and a selected shim of suitable thickness provides means for determining the lateral position of the wire with respect to the lay and hence the degree of tightness of the selvage.

This invention is capable of numerous forms and various applications without departing from the essential features herein disclosed. It is therefore intended and desired that the specific description herein be deemed illustrative and not restrictive and that the patent shall cover all patentable novelty herein set forth; reference being had to the following claims rather than to the particular showing herein to indicate the scope of this invention.

What is claimed is:

1. In a loom having a lay and heddles for manipulating warps for weaving a fabric, in combination, a lay,

means for inserting into an open shed the end of a weft extending from an edge of said fabric, and separate and distinct means for pulling the terminal portion of said inserted end through adjacent warps located a selvage-width distance from said edge of the fabric.

2. The combination set forth in claim 1 wherein said end-inserting means includes a pipe having a nozzle directed edgewise of said fabric and substantially central of said shed, a valve in said pipe, and means carried by said lay for actuating said valve in timed relation to the movement of said lay.

3. In a loom having a lay and heddles for manipulating warps for weaving a fabric, in combination, a lay, means for reciprocating said lay, means for blowing an end of a weft into an open shed, and a needle-like element mounted on said lay and extending upwardly therefrom in a plane perpendicular to the pivotal axis of said lay for movement through said warps as said lay is reciprocated, said element having a hook for engaging and pulling the terminal portion of said blown-in end through adjacent warps.

4. In a loom having a lay and heddles for manipulating warps for weaving a fabric, in combination, a lay, means for inserting into an open shed the end of a weft extending from an edge of said fabric, means for pulling the terminal portion of said inserted end through adjacent warps located a selvage-width distance from said edge of the fabric, said pulling means comprising a hook member extending upwardly from said lay in a plane perpendicular to the pivotal axis of said lay for movement through said warps as said lay is reciprocated, and means adjustably supporting said hook member on said lay whereby the distance of said hook member from the fell of the fabric for any given position of the lay with respect to the fell may be varied.

5. In a method for forming a selvage edge for a woven fabric, the steps comprising turning into an open shed an end of a weft disposed to the outer side of a marginal warp entering a fabric, closing the shed on the turned-in end of the weft, drawing the terminal portion of said turned-in end through adjacent warps located at selvage-width distance from said marginal warp, and binding in and beating up the portion of said turned-in end remaining in said fabric.

6. In a method for forming a selvage edge for a woven fabric, the steps comprising blowing into an open shed the end of a weft which extends beyond a warp at the edge of a fabric being woven, closing the shed on said blown-in end, hooking said blown-in end by a hook moving in a plane perpendicular to said warps and located at selvage-width distance from said edge and thereby drawing the terminal portion of said blown-in end through said warps, and reversing said warps to bind into the fabric the length of said end held by said warps.
